United States Patent Office.

NATHAN P. MULLOY, OF WALTHAM, MASSACHUSETTS.

Letters Patent No. 61,556, dated January 29, 1867; antedated January 19, 1867.

IMPROVED KNIFE-CLEANER.

The Schedule referred to in these Letters Patent and making part of the same.

TO ALL PERSONS TO WHOM THESE PRESENTS SHALL COME:

Be it known that I, NATHAN P. MULLOY, of Waltham, in the county of Middlesex, and State of Massachusetts, have made a new and useful Invention for Cleaning or Polishing Knives or Cutlery; and do hereby declare the same to be fully described in the following specification, and represented in the accompanying drawings, of which—

Figure 1 is a front elevation.

Figure 2, a side elevation; and

Figures 3 and 4, longitudinal and vertical sections of it.

In the said drawings, A is a base-block of metal, which may be provided with any suitable means of fixing it firmly to a table, post, or bench, such means as shown in the drawing being a bent arm, B, extended downward from the said block A, and provided with a clamp-screw, C, screwed upward through it, the said arm and screw being formed and arranged relatively to the block, as exhibited in the drawings. The said block may have a shape analogous to that of an anvil. There projects from the front side of the part A an extension, g, which has a vertical slot or socket, h, made in it for the reception of a piece of sole-leather, i, which is for the purpose of cleaning the surface of a fork or other article of cutlery, which cannot well be inserted between the other cleaning surfaces to be hereinafter described. The said extension, g, and the part A in its front and two ends, are surrounded by a trough, k, which has slots, l l, made down through it close to the ends of the part A, such slots being for the reception of a strip of leather, E, employed to cover the upper surface of the bed A. This piece of leather is held in place by tacks or pins, m m, driven through those parts of it which extend below the trough. There projects upward from the rear part or side of the base A a guide or ledge, n, which serves as a means of keeping a knife in its proper position between the adjacent polishing surfaces while it may be in the act of being cleaned by them. There extends upward from the base block A, in manner as represented in the drawings, a goose-neck or curved arm, F, which terminates in a cylinder, a, arranged as shown in the figures. A rod, G, slides vertically through the said cylinder, and its foot is pivoted in a step, b, formed in a projection, c, extended upward from the middle of a dished plunger, H. A spring, I, enveloping the said projection and rod and bearing against the goose-neck and the bottom of the space o within the plunger, serves to press the plunger down toward the bed A. The lower side or surface of the plunger is to be faced with leather, p, and there should hang from one end of such plunger an apron or piece of leather, q, the purpose of which is to prevent loss of the sand or polishing material used in cleaning the upper surface of a knife. The apron by resting on the knife will arrest the polishing or cleaning powder discharged from the knife while being drawn from between the polishing surfaces, and will cause or aid in causing it to fall down into the trough. The bottom of the dished plunger and the leather applied to such bottom are perforated with holes to let the polishing or cleaning powder placed within the plunger pass down upon the knife as well as upon the polishing surface of the bed.

In using this machine, a knife to be polished or cleaned is to be inserted between the leathers of the bed and plunger and quickly moved longitudinally back and forth, the plunger having previously been supplied with powdered brick-dust, rotten-stone, or emery, or other suitable material. The step b and the lower end of the rod G should be so formed as to allow the plunger to rock or tilt, so as to accommodate itself to the upper surface of a knife-blade, when such blade may be on the bed-polishing surface.

I make no claim to the invention described in the United States Patent No. 20,391, dated May 25, 1858.

What I claim as my invention, is—

My improved knife-polisher, as made with the fork-cleaner, or, in other words, the piece of leather i and its supporter h, arranged and combined with the knife-polishing bed and its plunger, applied and to operate together substantially as set forth.

I also claim the combination of the trough k with the knife-polishing bed and plunger, applied together in manner and so as to operate as explained.

I also claim the combination and arrangement of the leather-receiving slots l l with the trough k, the bed A combined with the plunger as set forth.

I also claim the arrangement and combination of the apron q with the plunger, bed, and trough, arranged and combined substantially as set forth.

I also claim the arrangement and combination of the guide n with the bed A and the plunger H, when arranged and combined as and for the purpose set forth.

N. P. MULLOY.
